We claim the ornamental design for an air moving apparatus, as shown and described.

DESCRIPTION

FIG. 1 is a perspective view of an air moving apparatus according to the present invention;

FIG. 2 is a right side view of the air moving apparatus of FIG. 1;

FIG. 3 is a left side view of the air moving apparatus of FIG. 1;

FIG. 4 is a front view of the air moving apparatus of FIG. 1;

FIG. 5 is a rear view of the air moving apparatus of FIG. 1;

FIG. 6 is a top view of the air moving apparatus of FIG. 1; and,

FIG. 7 is a bottom view of the air moving apparatus of FIG. 1. The broken lines shown in the drawings illustrate environmental structure and form no part of the claimed design.
